UNITED STATES PATENT OFFICE.

SHERMAN W. LADD, OF BEVERLY, MASSACHUSETTS, ASSIGNOR TO SIDNEY W. WINSLOW, TRUSTEE, OF BEVERLY, MASSACHUSETTS.

BUFFING-MACHINE.

SPECIFICATION forming part of Letters Patent No. 721,052, dated February 17, 1903.

Original application filed August 16, 1897, Serial No. 648,389. Divided and this application filed March 5, 1902. Serial No. 96,753. (No model.)

To all whom it may concern:

Be it known that I, SHERMAN W. LADD, of Beverly, in the county of Essex and State of Massachusetts, have invented an Improvement in Buffing-Machines, of which the following description, in connection with the accompanying drawings, is a specification, like letters on the drawings representing like parts.

10 The present invention relates to a machine for buffing the soles of boots and shoes, and is intended as an improvement on machines of the class shown in patent to Webster, No. 490,419, dated January 24, 1893.

15 The present invention relates especially to the construction of the spindle for carrying the abrasive pad and the parts directly coöperating therewith, said spindle having its bearings in a bracket adapted to be attached 20 to the framework of the machine.

The spindle has connected therewith a foot provided with a clamp to hold a flexible hollow expansive pad provided with an abrasive cover in the form of a disk which is rotated 25 rapidly by said spindle, the flexible pad constituting a yielding cushion to support the abrasive material against the pressure of the boot or shoe sole presented to it to be buffed.

30 The pad is hollow, and the spindle and its bearing-bracket are so constructed as to provide for the admission of air from the framework of the machine, so as to inflate the pad in order to provide the proper yielding support for the abrasive cover.

35 Figure 1 is a side elevation of a portion of the buffing-machine embodying this invention, and Fig. 2 a longitudinal section of the lower portion thereof.

40 The spindle *a*, provided with a driving-pulley *a*², runs in bearings *b* *b*², secured in a bracket *c*, provided with an arm or stem *c*², adapted to be fastened in the framework of the machine by which the spindle *a* is supported and operated. The stem *c*² and upper portion of the bracket *c* are provided with 45 an air-passage (shown in dotted lines at *c*³) leading to a cap *c*⁴, into which the upper end of the spindle *a* extends, said spindle being itself provided with longitudinal bore or pas-

sage *a*³, (see Fig. 2,) which communicates 50 with the passage *c*³ in the bracket, the cap *c*⁴ of which is provided with a stuffing-box *c*⁵ to cause the air supplied through the passage *c*³ to pass through the passage *a*³ in the spindle, so as to inflate the pad secured to the lower 55 end thereof.

The pulley *a*² for the spindle is made as a part of a sleeve *a*⁴, which surrounds the spindle between the bearings *b* *b*² and is secured to the spindle, so as to rotate the same and 60 also to prevent endwise movement thereof.

Below the lower bearing *b* the spindle *a* is provided with a flange *a*⁵, (see Fig. 2,) which engages with a flange in a threaded clamping-nut *d*, adapted to screw upon the upper 65 end of a threaded sleeve *e*, provided at its lower end with a wide flange *e*², surmounted by a narrower flange *e*³ with an intervening groove or channel, said flanges serving to receive between them the upper wall *f*² of the 70 hollow flexible pad *f* and constituting a pad-holding foot.

The nut *d* is fitted to the bearing *b* of the spindle, so as to afford a substantially dust-proof joint between the rotating and non-rotating parts, said bearing being shown as provided with a sleeve-like projection entering a corresponding groove in the adjacent face of the nut, which rotates with the spindle when the buffing device is in operation. 75

A clamping-plate *g* is supported upon the sleeve *e*, so as to be capable of moving up and down thereon, and is recessed in its lower portion, so as to receive within it the upper flange *e*³ of the pad-holding foot, while the 85 periphery of said clamping-disk *g* bears upon the edge of the abrasive cover *h* and upon the upper wall *f*² of the pad *f*, so as to clamp the pad and abrasive cover between the said clamping-disk *g* and the flange *e*² of the 90 clamping-foot. The clamping-disk *g* is forced down to clamp the pad and abrasive cover between it and the foot by means of a nut *k*, working upon the screw-thread of the sleeve. Thus the hollow flexible pad, which is commonly made of molded india-rubber, may be fastened air-tight upon the end of the threaded sleeve *e*, which is itself secured to the hol- 95

low spindle *a* by the nut *d* engaging with the upper portion of the thread of said sleeve, which is provided with a longitudinal notch engaging with a pin *a*⁶ on the hollow spindle 5 to secure the sleeve against rotation upon the spindle.

The pad *f* is not wholly impervious to the escape of air, so that the air is not, strictly speaking, confined therein, but flows slowly 10 therethrough, maintaining a sufficient pressure to distend the pad and yieldingly support the abrasive cover *h* without putting them under severe expansive strain.

Any suitable abrasive pad-cover may be 15 used; but the pad-covers are preferably molded and provided with an inturned flange constructed to form a series of tongues which are inserted between the clamping-disk *g* and the upper wall of the pad, so that said clamping- 20 disk serves both to clamp the abrasive cover on the pad and also to secure an air-tight connection between the pad and the sleeve

through which the air for inflating the pad is introduced.

I claim—

The combination with the pad-actuating spindle; of a supporting-bracket provided with bearings therefor; a flange on the spindle; a screw-threaded sleeve surrounding the end of the spindle; and a nut cooperating 30 with said sleeve and said flange for fastening the said sleeve to said spindle; a flanged foot carried by said sleeve; a clamping-disk cooperating with said flanged foot; and a nut for actuating the said disk working on the 35 said threaded sleeve, substantially as described.

In testimony whereof I have signed my name to this specification in the presence of two subscribing witnesses.

SHERMAN W. LADD.
